UNITED STATES PATENT OFFICE.

JOHN E. BROWNE, OF ALLSTON, MASSACHUSETTS.

VALVE MECHANISM FOR INTERNAL-COMBUSTION ENGINES.

1,096,596.

Specification of Letters Patent.

Patented May 12, 1914.

Application filed August 6, 1913. Serial No. 783,276.

To all whom it may concern:

Be it known that I, JOHN E. BROWNE, a citizen of the United States of America, residing at Allston, in the county of Suffolk and State of Massachusetts, have invented certain new and useful Improvements in Valve Mechanism for Internal-Combustion Engines, of which the following is a specification.

10 This invention relates to a valve mechanism for internal combustion engines and has for its object, the provision of an improved device of this character in which a single valve controls both the intake and the 15 exhaust from three cylinders.

It is a further object of the invention to provide a valve of the type indicated which shall be entirely rotative in its movement in contradistinction to the ordinary puppet 20 type of valve and in which means are provided for permitting expansion or separation of the valve members with relation to each other when the metal, constituting said valves, expands, and conversely for drawing 25 these valve members together when the engine cools.

It is a further object of the invention to limit such latter movement to prevent the valve members from being drawn too far 30 toward each other.

Further objects and advantages of the invention will be set forth in the detailed description which now follows.

In the accompanying drawings, Figure 1 35 is a view partly in side elevation and partly in section of a part of a six cylinder engine constructed in accordance with the invention, Fig. 2 is a longitudinal sectional view therethrough upon the line of one of the 40 valve members, Fig. 3 is a transverse vertical sectional view, Fig. 4 is a detail sectional view of one of the valves, and Fig. 5 is an underside face view of the valve containing cylinder head.

45 Like numerals designate corresponding parts in all of the figures of the drawings.

In the drawings, the numerals 5 designate six cylinders arranged in two sets of three cylinders each, each set of cylinders being 50 preferably cast *en bloc*. The exhaust and intake from all of the cylinders of a set are controlled by the single valve shown in Fig. 4. These valves comprise intake ends 6 and exhaust ends 7. Each end of the valve is of 55 cup-like formation, frusto-conical in form and open at its outer end.

A shaft 8 is secured by head 9 and screws 10 to the inner face of the exhaust end of the valve. This shaft is preferably angular in cross section so that the intake end is caused to rotate with the shaft while being capable of a limited longitudinal movement with relation thereto. A spring 11 bears between the inner face of the intake end and a washer 12 mounted upon the shaft 8. A nut 13 is 60 threaded upon the shaft outside of the washer and is held against accidental displacement by a pin 14. Fitted upon the angular shaft is the hub 15 of a worm wheel 16. This hub serves to limit the movement 65 of the intake end 6 of the valve toward the exhaust end 7. Rings 17 are carried by the hub 15, said rings having ways formed there-in for the reception of anti-friction balls 18. Rings 19 having ways formed there- 70 in receive these balls, said rings and balls 75 providing anti-friction mounting for the valves.

As is best illustrated in Figs. 1, 2 and 3, the cylinder head consists of a hollow cap 20 80 divided by a wall 21 into chambers 22 and 23. A central pocket 24 is in communication with chamber 23 and in this pocket, worm wheel 16 is disposed, said pocket serving to receive oil to provide efficient and constant 85 lubrication of the parts. A worm 25 meshes with worm wheel 16, said worm being mounted upon a shaft 26 driven in any desired manner from the main shaft of the engine (not shown). This shaft is prefer- 90 ably provided with ball bearings 27. A cap plate 28 covers the chamber 23. Chamber 22 constitutes a water space through which a cooling medium may be circulated for the purpose of cooling the valves and adjacent 95 parts. This water space is in communication with a second water space 29 which extends about the cylinders. Intake and exhaust conduits 30 and 31 extend through chamber 22 and lead from the cylinders to 100 the seats of the valve ends (see Fig. 3). The valve ends each have a pair of ports 32 and 33, by virtue of which construction it is necessary for the valve to turn only one revolution to four revolutions of the crank shaft, 105 the angular displacement of ports 33 with relation to ports 32 being such that the proper timing of the engine is had to permit the operation thereof upon the four-stroke cycle.

110 Communicating with the open end of the intake end of the valve is an intake manifold

34 and communicating with the open end of the exhaust end of the valve is an exhaust manifold 35. It will be noted that these manifolds are slightly recessed at 36 to permit the desired endwise movement of the valve ends, it being understood that as the metal expands, the valves are permitted the necessary slight outward movement by reason of the yielding mounting of the valve ends with relation to each other. When the metal of the valve contracts, these valves move toward each other, but as before stated, this latter movement is limited by the hub 15 which is interposed between the valve ends.

15 From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims.

Having described my invention, what I claim is:

1. A valve for internal combustion engines, consisting of a pair of hollow, frusto-conical members having their smaller ends disposed toward each other, an angular shaft fixed to one of said members and extending through the other of said members, an enlarged portion carried by said shaft, a spring bearing between said enlarged portion and one of said frusto-conical members, and a driving member mounted upon said shaft, said driving member limiting the movement of said frusto-conical members toward each other.

2. In a device of the character described, the combination with a pair of hollow, frusto-conical members, one of which constitutes an intake end and the other of which constitutes an exhaust end and each of which has a pair of ports formed through its side walls in diametrically opposed relation, of a shaft fixed to one of said ends and extending through the other of said ends, a member carried by said shaft, a spring bearing between said member and the inner face of the end through which said shaft passes, means for causing said last named end to turn with said shaft and a driving member mounted upon said shaft between said ends. 55

3. In a device of the character described, the combination with a pair of hollow, frusto-conical members, one of which constitutes an intake end and the other of which constitutes an exhaust end and each of which has a pair of ports formed through its side walls in diametrically opposed relation, of a shaft fixed to one of said ends and extending through the other of said ends, a member carried by said shaft, a spring bearing between said member and the inner face of the end through which said shaft passes, means for causing said last named end to turn with said shaft, a driving member mounted upon said shaft between said ends and anti-friction members disposed between said valve ends and providing an anti-friction mounting for said valve. 65

In testimony whereof I affix my signature in presence of two witnesses.

JOHN E. BROWNE.
